W. C. HUNTOON, JR.

COLLAPSIBLE TUBE

Filed April 17, 1925

Inventor
William C. Huntoon Jr.
By Joseph A. Miller
Attorney

UNITED STATES PATENT OFFICE.

WILLIAM C. HUNTOON, JR., OF EAST GREENWICH, RHODE ISLAND.

COLLAPSIBLE TUBE.

Application filed April 17, 1925. Serial No. 23,849.

To all whom it may concern:

Be it known that I, WILLIAM C. HUNTOON, Jr., a citizen of the United States, residing at East Greenwich, in the county of Kent 5 and State of Rhode Island, have invented new and useful Improvements in Collapsible Tubes, of which the following is a specification.

This invention relates to certain new and 10 useful improvements in captive tops for collapsible tubes, and the primary object thereof is to provide novel means for enabling positive anchoring of the means which hingedly and rotatably connects the cap to 15 the tube, so as to prevent bodily rotation of such means during screwing and unscrewing of the cap in moving the latter to closed and open positions.

A further object of the invention is to 20 provide anchoring means which enables the hinging means to be located at any desired point about the neck, and then firmly secured in the selected position.

The invention still further aims to provide means of the character described which is of simple and economical construction, and which enables the cap holding means to be easily and quickly applied and effectually anchored in the selected position. 25

30 In the drawings:—

Figure 1 is a fragmentary side elevation of a tube showing the present invention applied thereto;

Figure 2 is a top plan view; and

35 Figure 3 is a rear elevation.

In proceeding in accordance with the present invention, the tube body 1, is shown provided with the usual base or skirt 2, that flares downwardly from the neck 3, the mouth of the neck being closed 40 excepting as to an elongated slot 4, which extends diametrically across the mouth. A collar 5 is formed on the neck and disposed in spaced relation to and above the top of the skirt 2, to form a groove 6.

The means for hingedly and rotatably connecting the cap 7, to the tube, consists of a piece of wire formed intermediate its ends with a straight bar 8, and having its 45 ends 10 engaged about the neck and disposed in the groove 6, in embracing relation to the neck. The bar 8, affords a pivotal mounting for the attaching means of the cap, as will now be described.

50 The cap 7 is provided with a flared collar 11, providing a circular groove 12, in con-

junction with the under face of the head of the top. A second piece of wire is employed, which is bent intermediate its ends to form a series of coils 13, which receive 55 the straight bar 8 therethrough and tend to tension the wire upon the bar 8 while the ends 14, of the wire are disposed about the cap and in the groove 12 thereof so as to permit of rotation of the cap in screwing 60 same into and out of engagement with the threads of the neck of the tube. The wire ends are crossed at 15°, so as to cause the wire ends to more effectually engage about the cap. 65

In order to secure or anchor the first wire member to the neck of the tube so as to prevent rotation thereof, the ends 10 are disposed in spaced relation, as depicted in Figs. 2 and 3, of the drawings. The member is 70 then rotated to locate or position same in desired relation to the usual printed matter which appears on or is embossed on the surface of the tube 1, following which the collar 5 is depressed between the points 75 15-15 at 16 the distance existing between the ends 10, the part 16 of the collar approximately equalling the distance between the spaced ends 10, whereupon the part 16, is bent or forced downwardly so as to provide 80 an abutment which engages the ends 10, and holds the wire against rotation. It is evident that the whole of the collar surrounding the tube may be depressed upon the wire if desired without departing from the 85 spirit of the invention. 90

Due to the fixed holding of the coils 10 on the base of the neck, the cap is always held in its correct relation to the neck threads when swung to engage the latter, the cap 95 being held against oscillations at right angles to the tube axis thereby rendering it easier to mesh the cap and neck threads, and also preventing bending of the part 10 or distortion thereof. 100

Having thus described my invention, what I claim as new and desire to secure by Letters Patent is:—

1. In combination with a collapsible tube having a collar spaced above the neck base, to form a groove, a wire in the groove having its ends spaced apart and having an intermediate straight part, a cap formed with a circular groove, and a second wire having an intermediate part coiled about 105 the straight part of the first wire and engaged with the neck base and having its 110

ends crossed and engaged in the groove of the cap in embracing relation thereto, said collar of the tube neck having a portion thereof equalling approximately the distance between the spaced ends of the first wire extended downwardly to lie in the space between the ends of the first wire so as to engage such ends and hold the first wire against rotation.

- 10 2. In combination with a collapsible tube having a collar spaced above the neck base, a wire member having its ends spaced and disposed in the groove in embracing relation to the neck, said collar having a portion disposed in the space between the wire ends to engage the latter and hold the wire member against rotation, a cap, and means rotatably connected to the cap and hingedly connected to the wire member and engaged 15 with the neck base to swingingly and rotatably mount the cap relative to the neck.
- 20 3. In combination with a collapsible tube

having a groove in its neck, a split member disposed in the groove and having its ends spaced, said neck having a part thereof projecting into the space between said member ends and engaging each of the latter to hold the member against rotation, a cap, and means swingingly connected to the member and connected to the cap so as to permit the latter to rotate.

25 4. In combination with a collapsible tube and a cap therefor, a member engaged about the neck, means to rigidly hold the member against rotation, and means engaging the cap to rotatably mount same and having a part movably connected to said member and movably engaged with the base of the neck so that the latter affords a fixed point about which the cap mounting means 30 swings.

35 In testimony whereof I have signed my name to this specification.

WILLIAM C. HUNTOON, JR.
